United States Patent Office

Des. 188,164
Patented June 7, 1960

188,164

ICE CRUSHER

Henry J. Talge, Kansas City, Mo., and Sheldon M. Rutter, Miami, Fla., assignors to John C. Hockery, trustee, Kansas City, Mo.

Filed Nov. 2, 1959, Ser. No. 58,147

Term of patent 14 years

(Cl. D89—1)

Fig. 1 is a front elevational view of an ice crusher embodying our new design;

Fig. 2 is a side elevational view of same;

Fig. 3 is a rear elevational view of same; and

Fig. 4 is a top plan view of same.

The essential features of our design reside in the portions shown in solid lines.

We claim:

The ornamental design for an ice crusher, as shown and described.
